UNITED STATES PATENT OFFICE

JOHN M. YOUNG, OF BROOKLYN, NEW YORK, ASSIGNOR TO AMERICAN CAN COMPANY, OF NEW YORK, N. Y., A CORPORATION OF NEW JERSEY

COMBINATION TEARING STRIP AND FRICTION CLOSURE CAN

Application filed November 2, 1925. Serial No. 66,228.

This invention relates to tearing strip cans of the type shown in my co-pending application Serial No. 742,999, now Patent No. 1,586,277 May 25 1926 and has for its principal object the provision of a can constructed to provide the advantages of the structure of said co-pending application and also to provide a plurality of seals between the cover and can body both sealing the can at the same time prior to the removal of a tearing strip by means of which the can is adapted to be opened.

It will be noted from the drawings and as the description progresses that one of said seals is provided by the double seam at the top end of the can and additional sealing by means of an inward bend in the body of the can, which is extended a considerable distance from the plane of the wall and is slightly yielding, having a spring action radially of the can so that it provides a tight contact with a friction element of the cover which it engages, this inwardly-bent portion being also rounded so as to provide a tight seal along a circumferential line of contact.

A further object of my invention is to arrange the ordinary countersink, provided for the double seaming which connects the cover to the can body, sufficiently deep to permit the horizontal extension from the base of the countersink practically to contact the upper portion of the inward bend or loop of the can body previous to the removal of the tearing strip, thereby providing a double seal closure after the tearing strip has been removed, wherein the position of the cover relative to the can is the same before and after the removal of the tearing strip, and the can remains of the same height under either condition.

Another object of this invention resides in forming the inner vertical wall of the top seam, which joins the cover to the body portion, sufficiently deep so as to provide a lining or backing for the rear face of the tearing strip and in forming the bottom portion of this vertical wall with an inwardly bent portion adapted to form a frictional seal with the resilient loop or bend of the body, where-

by effectively to exclude the contents of the can from the zone of the tear strip.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a can in which my invention is embodied;

Fig. 2 is a partial sectional view of the upper part thereof prior to the removal of the tearing strip, and

Fig. 3 is a similar view after the tearing strip is removed and the cover positioned as a friction plug reclosure.

On said drawings, illustrating the best manner in which I have thus far contemplated applying the principles of my invention, the reference character 11 indicates the body of a sheet metal can of the usual round form, though it will be manifest that the invention is equally applicable to cans of different shape. A bottom end 12 and an upper end or cover 13 are secured to the body in the sanitary double seamed or other usual manner and the upper part of the body wall is scored at 14 and 15 to provide a tearing strip 16 adapted to be removed to open the can. The double seam by which the upper end 13 is secured to the body wall is indicated at 17 and the usual side seam is shown at 18.

Just below the lower score line 14, the material of the can body is bent inwardly at 19 in the form of a hollow looped flange, as viewed in cross-section (see Fig. 2), and may be bent thence downwardly at 20, the material of the body wall above and beneath the loops being in the same plane, as may be readily seen from the drawing. The bend thus provided is open so that a rounded internal surface is provided for the reception of the friction plug cover, as will be presently described. The top 20' of the bent portion may extend over into contact or substantially into contact with the wall of the can above the lower score line and this serves to guard

the sharp edge resulting on the can body from the removal of the tearing strip.

The cover 13 has the usual countersunk portion adjacent the double seam which connects the cover to the body portion. This 5 countersunk portion is formed with a vertical wall 21 which extends downwardly and substantially in contact with the wall 16 at the zone of the tearing strip to provide a backing or lining for the rear of this tearing 10 strip. This wall 21 at its basal portion is provided with an inward extension 21', which practically engages the upper portion or top 20' of the loop or bend 20, and from this 15 point the wall then extends downwardly, as at 22, and engages the inner circumferential wall 23 of the bend or loop to form a frictional fit therewith. The wall then extends inwardly, as at 24, and thence upwardly, at 25, to provide the cover 13. It will thus 20 be seen from an inspection of Figs. 2 and 3 of the drawings that this construction results in a double sealed closure wherein the position of the cover 13 relative to the can is the same before and after the removal of 25 the tearing strip 16.

It must be further apparent that the advantages of this construction reside in the fact that no space is left in the can above the 30 loop or bead 20, since the downwardly-extending wall 21 is sufficiently deep to not only contact with the rear of the body wall at the zone of the tear strip, but also being provided with the inwardly and downwardly-bent portions 35 at its base, it forms a double seal with the bend or loop 20 at these points effectively to exclude the contents of the can from the wall of the can body at the rear of the tear strip. By means of this construction there 40 is no danger of any of the material in the container being moist and subsequently smearing on the edge of the loop or bend when the can is shipped. Therefore, in a can of this type, even though the contents 45 be a somewhat sticky liquid material, none of it will be present to smear the hands in opening the can. It will also be apparent that by excluding the contents of the can from the zone of the tear strip, when the 50 can is opened, there is no possibility of the contents exuding from the severed walls of the can body. It will also be apparent that the yielding or spring-action of the bend 19 provides a tight gripping of the walls 26 so 55 that after removal of the tearing strip the cover may be positioned, as in Fig. 3, in the manner of the ordinary plug closure.

The can is opened by engaging the tongue of the tearing strip 16 with the usual key 60 and winding up the tearing strip as severance along the lines 14 and 15 occurs.

It is thought that the invention and many of its attendant advantages will be understood from the foregoing description, and it 65 will be apparent that various changes may

be made in the form, construction and arrangement of the parts without departing from the spirit and scope of the invention, or sacrificing all of its material advantages, the form hereinbefore described being merely a preferred embodiment thereof. 70

I claim:

1. A can, comprising a body having score lines setting off a tearing strip around the body near its top, the material of the body being bent inwardly in a hollow looped flange below and near the tearing strip and to a distance beyond the rest of the interior surface of the body and forming an internal friction wall, and a cover having an external shoulder fitting tightly within the mouth of the body and a flange double-seamed with the top edge of the body and an external friction wall of less diameter than the said shoulder and fitting tightly within said internal friction wall of the body before the said tearing strip is removed. 75 80 85

2. A can, comprising a body having score lines setting off a tearing strip around the body near its top, the material of the body being bent inwardly in a hollow looped flange below and near the tearing strip and to a distance beyond the rest of the interior surface of the body and forming an internal friction wall, and a cover having an external shoulder fitting tightly within the mouth of the body and a flange double-seamed with the top edge of the body and an external friction wall of less diameter than the said shoulder and fitting tightly within said internal friction wall of the body before the said tearing strip is removed, said cover also having a part which fits on the top of said looped flange. 90 95 100

3. A can comprising a body provided with encircling score lines setting off a tearing strip, the material of the body being bent upon itself to provide a friction wall within the can and of diameter less than the diameter of the portion of the body provided with said encircling score lines, and a cover seamed to the body and having a cylindrical wall engaging said portion of said body provided with said score lines and having also a substantially vertical friction seat wall inset from said first mentioned wall by the thickness of the bend and engaging within the friction seat wall of the body prior to the removal of said tearing strip. 105 110 115
